UNITED STATES PATENT OFFICE.

JOHN GRAY, OF NEWCASTLE-UPON-TYNE, ENGLAND, ASSIGNOR TO R. & W. HAWTHORN, LESLIE & COMPANY, LIMITED, OF NEWCASTLE-UPON-TYNE, ENGLAND.

MANHOLE-FITTING.

1,382,187.

Specification of Letters Patent. Patented June 21, 1921.

Application filed June 11, 1919. Serial No. 303,358.

To all whom it may concern:

Be it known that I, JOHN GRAY, a subject of the King of the United Kingdom of Great Britain and Ireland, and residing at 5 Newcastle-upon-Tyne, England, have invented a certain new and useful Improvement in Manhole-Fittings, of which the following is a specification.

This invention relates to improvements in 10 manhole fittings applicable particularly to steam generators but also suited for vessels, tanks and like structures necessitating the use of a compensating plate to be engaged on one side of the generator or the like by 15 the door which is passed through the manhole from the other side and is maintained in closing position by means controllable from the second mentioned side.

The invention has for an object to provide 20 a construction which permits reduction of the size of the hole to be cut in the shell; a further object is to avoid the necessity for flanging the compensating plate; other objects will appear from the following description.

According to the invention there is 25 formed in the interior face of the compensating plate a groove bounding the hole and the margin of the door is overturned to form an outwardly directed flange to engage the 30 groove and form a joint therewith.

In the accompanying drawings Figure 1 is an inside view of the door frame; Figs. 2 and 3 are sections at right angles to each 35 other showing the door fitted to the frame.

Referring to the drawings, it will be seen that the compensating plate 1, which may be of substantially the same tensile strength

as the boiler shell 2, in lieu of being flanged, is formed on its interior face adjacent to its 40 inner edge with a groove 3 bounding the hole; the margin of the door 4 being overturned to form an outwardly directed flange 5 adapted to engage the groove 3 and form a joint therewith.

A door constructed as described may be of small dimensions and lighter than in prior constructions, and may be more easily put in place, besides being readily removable without disturbance of the joint. Evidently, the compensating plate may be of 50 smaller dimensions than in prior constructions. In addition, the combined sectional area of the rivets 6 may be less than heretofore and the rivets may be conveniently 55 machine riveted.

What I claim is:—

In a manhole fitting, the combination with a shell having a manhole, of a compensating plate riveted to the interior of 60 said shell, said plate formed with a hole opposite said manhole of smaller area than said manhole, said plate having in its interior face a groove bounding said hole, and a door having an overturned marginal flange 65 engaging said groove and forming a joint therewith, the area defined by the inner edge of said flange being no greater than the area of said manhole.

In testimony whereof I have signed my 70 name to this specification in the presence of two subscribing witnesses.

JOHN GRAY.
